UNITED STATES PATENT OFFICE

ROSE B. ZIMMERMAN, OF CHICAGO, ILLINOIS

SPRING CONSTRUCTION

Application filed December 5, 1930. Serial No. 500,176.

This invention relates to spring construction and particularly inner spring construction for mattresses, cushions, davenport, chair seats and other similar articles.

The primary object of the invention is to provide a new and novel spring construction for mattresses, cushions, and the like, which construction makes the springs more resilient and provides for a hinge connection between individual spring members.

Another object of the invention is to provide an improved spring construction which causes the individual springs to contract according to the weight carried by each spring without transmitting contraction to other springs.

Another object is to provide a new and novel method for connecting springs, whereby there is a resilient or flexible tie connection between individual springs so that the weight applied to a single spring will be relieved by the tie connection and not transmitted to other springs.

A further object is to provide an inner spring construction for mattresses whereby the springs are arranged in sets or gangs, the springs of each section or gang having their sides adjacent and hingedly connected together by a crimped or resilient tie wire.

A still further object is to provide a spring of spiraled construction having upper and lower contacting surfaces relatively circular with oppositely disposed relatively straight edges.

Numerous other objects and advantages will be apparent throughout the progress of the following specification.

The invention comprises in general a spiral coiled spring of the usual construction which is commonly used for bedsprings, mattresses, cushions, and the like. The upper circular contacting portions of the springs are provided with oppositely disposed straight edges. The springs are arranged in sets or gangs with the straight edge of one spring arranged adjacent a straight edge of another spring. Each set or gang of springs is connected with a longitudinal tie wire. This tie wire passes about the adjacent straight edges of the springs in each gang. At one edge of the ad-

jacent straight surfaces the tie wire has a right hand turn and at its other edge has a left hand turn. This spring tie wire is continuous and connects the various sets or gangs of springs. The tie wire between each set or gang of springs is crimped to provide resiliency between sets or gangs. The adjacent straight edges which are connected by the tie wire permit for a hinge connection between adjacent springs of each set or gang. This construction provides a strong and efficient means for connecting the springs together, forms a hinge connection between adjacent springs in each set or gang, and causes a flexible or resilient connection between each set or gang. Springs of this type connected by the particular tie wire heretofore mentioned causes the complete spring assembly to conform to the shape of the body and prevents weight transmitted on a certain number of individual springs from being transmitted throughout the entire spring assembly.

The accompanying drawings illustrate a selected embodiment of the invention and the views therein are as follows:

Fig. 1 is a detail plan view of a spring construction embodying the invention.

Fig. 2 is a detail view of a tie wire disconnected from the individual springs.

Fig. 3 is a detail sectional view through a mattress employing the improved spring construction.

Fig. 4 is a detail perspective view showing the manner in which the springs of each set or gang are connected together by a tie wire having a right and left hand wind.

Fig. 5 is a detail elevation of a pair of individual springs showing the hinge connection between adjacent springs of each set or gang.

Referring to the drawings, 6 designates a mattress, cushion, or other like article having pads 7, 7 arranged above and below the inner springs 8. The pads 7 comprise two layers of ticking 9 between which a filler 10, such as felt, hair, or the like, is arranged. A side pad 11 extends about the sides and edges of a completed spring assembly, having upper and lower rolled edges 12, 12 which are fastened to the pads 7 in the usual manner.

The springs 8 are of the usual spiral coiled type having upper and lower contacting or engaging surfaces 13, 13. The top and bottom or engaging surfaces 13 of each individual spring are preferably arranged in longitudinal sets or gangs 14, Fig. 1.

Each spring 8 has oppositely disposed straight sides 15 on its upper and lower surface which are adapted to engage the straight sides of adjacent springs in each set or gang.

Transverse tie rods 16 pass about the adjacent straight edges of two springs of each set or gang and operatively connect each set or gang together, providing a hinge connection between adjacent springs in each set or gang. The tie wire 16 is wound about the straight edges 15 of adjacent individual springs (providing a hinge connection) as indicated at 17 and 18, Figs. 1 and 4. The wind 17 is right handed as indicated at 19, Fig. 4, while the wind 18 is left handed as designated at 20. This right and left handed winding holds the springs of each set together, prevents the edges of the springs from overlapping, and permits a hinged connection between adjacent springs of each set or gang.

Between each set or gang 14, the tie wire 16 is provided with a plurality of crimps 21 for providing a relatively resilient connection between each set or gang. Therefore, when a weight is applied to any number of springs, the adjacent springs are permitted to contract or flex as shown in Fig. 5, thereby preventing a plurality of other individual springs from flexing or contracting. The tie wires 16, due to their resiliency caused by the crimps 21, prevent the springs in another gang or set from flexing or contracting, as the depression of one spring is taken up by the connecting tie wire and not transmitted to the next gang or set. Also the part 22 of the spring, which is that part between the coils 17 and 18, assists in holding the straight edges 15 of adjacent springs together and adding strength thereto.

The tie wires 16 connect contiguous springs in each set and also connect each set. Between each set these tie wires are crimped and provide elasticity or resiliency between each set or gang. Therefore, a pressure on any one or any plurality of springs is taken up by the tie wires instead of being transmitted to other springs. The tie wires are continuous, running from one end of the spring completely across to the other end, forming a tie connection between contiguous springs and also forming a tie connection between individual sets. This provides a durable construction for the spring assembly.

The present spring construction provides a spring which is noiseless and eliminates all squeaking. The tie wires 16 are directly connected to each set or gang and made continuous, thereby preventing a plurality of loose connections to cause noise and squeaks

as is found in the conventional type of spring.

The straight edges 15 of the springs are circular in cross section and the outer rounded edge of one straight side is contiguous with the rounded edge of a straight side of an adjacent spring. Therefore, when a pressure is applied to one spring, the two contacting rounded surfaces will ride over one another reducing friction and preventing squeaks and noises.

The inner spring construction herein shown is applicable to all articles to which the invention may pertain, but is particularly adaptable for bed-springs, mattresses, cushions for automobiles, furniture cushions and all other similar articles.

The invention provides a spring construction, particularly an inner spring construction for mattresses, cushions, and the like, which is more resilient, makes the springs shape to the body, and prevents the contraction of an individual spring, or springs, upon which a weight is applied from being transmitted throughout the entire spring assembly.

The straight opposite edges on the upper and lower surfaces of the springs permit a hinged connection between adjacent springs and prevents the upper and lower coils of one spring from overlapping an adjacent spring. The tie wire prevents the contraction or deflection of the springs in one set or gang from being transmitted to another set or gang, due to the flexibility of the tie wire between sets or gangs caused by the crimping. The right and left wind about the straight edges of adjacent springs tends to hold the edges of the springs in position, prevents the edges of the springs from overlapping, and makes an efficient and sturdy spring construction.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

1. A spring assembly comprising a plurality of coiled springs arranged in parallel spaced rows, the top coil of each spring in a row having on each side in the row an offset portion providing first and second separated shoulder portions extending toward the adjacent spring of the row connected by a substantially straight portion, the straight portions of adjacent springs of a row being in contact throughout a substantial portion of their length, and tie wires extending transversely of the rows and connecting adjacent pairs of one row to corresponding adjacent pairs in the adjacent rows, the tie wire being looped about the straight contacting portions adjacent the first shoulder portion and reversely looped about said contacting

portions adjacent said second shoulder portion, the portions of the tie wire extending between the spaced rows being provided with resilient bends in the upper surfaces of the 5 spring assembly whereby adjacent spaced rows are resiliently connected.

2. A spring assembly comprising a plurality of coiled springs arranged in parallel spaced rows, the top coil of each spring in a 10 row having on each side in the row an offset portion providing first and second separated shoulder portions extending toward the adjacent spring of the row connected by a substantially straight portion, the straight portions of adjacent springs of a row being in 15 contact throughout a substantial portion of their length, and tie wires extending transversely of the rows and connecting adjacent pairs of one row to corresponding adjacent pairs in the adjacent rows, the tie wire 20 being looped about the straight contacting portions adjacent the first shoulder portion at least twice and reversely looped about said contacting portions adjacent the second shoulder portion at least twice, the portions 25 of the tie wire extending between the spaced rows being provided with resilient bends in the plane of the upper surface of the spring assembly whereby adjacent spaced rows are 30 resiliently connected.

In witness whereof, I have hereunto subscribed my name.

ROSE B. ZIMMERMAN.
